UNITED STATES PATENT OFFICE.

LEON STRAUSS AND ANNA STRAUSS, OF ANNAPOLIS, MARYLAND.

DESIGN FOR A CHILD'S SWEATER SUIT.

Application filed October 10, 1922. Serial No. 3,923. Term of patent 3½ years.

To all whom it may concern:

Be it known that we, LEON STRAUSS and ANNA STRAUSS, citizens of the United States, residing at Annapolis, in the county of Anne Arundel and State of Maryland, have invented a new, original, and ornamental Design for a Child's Sweater Suit, of which the following is a specification, reference being had to the accompanying drawings forming a part thereof, in which:

The parts are lined to indicate red, although the colors may be varied.

We claim as our invention:

The ornamental design for a child's sweater suit, as shown and described.
